UNITED STATES PATENT OFFICE.

LESHER W. VAN BUSKIRK AND PHILIP W. PORTER, OF HIGH BRIDGE, NEW JERSEY,
ASSIGNORS TO TAYLOR-WHARTON IRON AND STEEL COMPANY, OF HIGH BRIDGE,
NEW JERSEY, A CORPORATION OF NEW JERSEY.

REVERSIBLE DIPPER TOOTH.

Application filed April 26, 1921. Serial No. 464,647.

To all whom it may concern:

Be it known that we, LESHHER W. VAN BUSKIRK and PHILIP W. PORTER, citizens of the United States, and residents of High Bridge, in the county of Hunterdon and State of New Jersey, have jointly invented certain new and useful Improvements in Reversible Dipper Teeth, of which the following is a specification, reference being made

10 to the accompanying drawings, forming a part hereof.

The most serviceable forms of digging teeth or so-called dipper teeth are those in which the bucket carried element and point are constructed in one piece, but of late years the practice has been to make them of sectional form embodying a base and a detachable and reversible point. This type is preferred for economical reasons because

20 the point is subjected to heavy wear and requires frequent reversal or replacement. Yet there is considerable dissatisfaction because no form of interlock has heretofore been proposed which did not inherently

25 weaken the base or which was sturdy enough to maintain the requisite rigidity to eliminate side wobbling and other forms of lost motion.

Objects of our invention are to provide

30 a dipper tooth of the sectional form in which breakage of the base is wholly eliminated, or at any rate reduced to the minimum, and which will maintain perfect rigidity of the point under all conditions of service.

35 The invention, generally stated, resides in the dipper tooth and in the elements of which it is embodied, all as hereinafter described and particularly pointed out in the claims.

40 Referring to the drawings,

Figure 1 is an elevational view, showing the base and point in assembled relation.

Fig. 2 is a section on line 2—2 of Fig. 1.

Fig. 3 is a perspective view of the point.

45 Fig. 4 is a longitudinal sectional view of a modification.

Fig. 5 is a section on line 5—5 of Fig. 4.

Fig. 6 is an elevational view of a further modification.

50 In the preferred construction, the base 1 is provided with the usual slot or recess 2

to accommodate the bucket, and with holes 3 to provide for the usual rivet connection. Its frontal part or nose is bifurcated, as is usual, to provide spaced point-receiving 55 arms or elements 4 of approximately triangular outline in side elevation, the juncture of the arms with the base proper presenting perpendicular abutments or shoulders 5 to be later more specifically referred 60 to. Each arm terminates in a tip 6 with the upper and lower walls 7 and 8 divergent therefrom to a point in advance of the shoulders 5 where said walls 7 and 8 are approximately parallel as at 9. The top and bottom walls of arms 4 are also outwardly inclined, as indicated at 10 in Fig. 2, so that in cross-section they are of general trapezoid or wedge formation. The throat or slot separating the arms is slightly flared, 70 as indicated at 11, to facilitate the introduction of the point, and the tips have angular bearing surfaces, as indicated at 12 in Fig. 4, to engage correspondingly formed recesses in the point.

75 The point 13 has a central longitudinally ranging web 14 adapted to snugly fit the space between the point-receiving arms 4, and also functioning to prevent spreading of the jaws of the points. The web has a 80 curved or arcuate terminal which fits the correspondingly curved crotch portion of the base. This materially assists in preventing relative movement of the point and base. The jaws and the web form laterally and 85 rearwardly opening notches or recesses 15 accurately contoured to accommodate the point-receiving arms 4, so that as the point is moved to position with the web between the arms there is a wedging action or substantially a dovetail connection between the point-receiving arms and their complementary recesses. The rear portions of the upper and lower walls of the dovetail notches 15, are flattened as at 16 to co-operate with the 95 approximately parallel portions 9 of the point-receiving arms, thus providing a substantial broad area of bearing to assist in preventing twisting movement of the point. The shoulders 5 of the base are in a plane 100 approximately at right angles to the plane of movement of the tooth in use, and the

ends 17 of the point abut squarely against these shoulders and thus take care of some of the end thrust.

The point-receiving arms 4 and the web 5 14 are provided with registering openings 18 to accommodate a transversely ranging pin or rivet 19 buttonheaded at its respective ends.

In Figs. 4 and 5, there is illustrated a 10 slight modification wherein the web 14 is provided with longitudinally extending ribs or panels 20 and the point-receiving arms 4 are provided with correspondingly grooved or channeled portions 21 with which the 15 ribs co-operate in the assemblage of the parts. Manifestly this construction affords an additional safeguard to twisting or turning movement of the point. Rigidity of the parts is also promoted by the angular 20 position of the tips 6 with respect to the extreme limits of the point recesses 15 with which they co-operate.

In Fig. 6, there is shown a further modification in that the shoulders 5 are formed on 25 lines substantially coincident with a line of curvature of which the apex of the point is the center, such shoulders and similar shoulders or stops 21 on the point mutually tend to resist end thrust and lateral thrust in a 30 manner obvious from the drawing.

In all constructions, we prefer to employ, as indicated in the drawing, a point having 35 full section jaws and a full section web, that is to say jaws which extend the full width of the point body and an unbroken longitudinal full section web which fully bridges the jaws. The full section jaws are essential to provide for the undercut areas which co-operate with the reverse bevels of the base. 40 The full section web eliminates spreading or warping and by filling the undercut area of the base, aids materially in uniformly transferring stresses to the base, and affords co-operative aid in preventing side wobble, 45 twisting movement, and other forms of lost motion. The sectional view of the point clearly indicates that the general design of the reverse bevels, considering the top and bottom sets, respectively, as entities, is that 50 of an arch. The effect and merit of this is that when the point is applied, the undercut portions of its full section jaws will exert substantial side pressure on the point-receiving arms.

55 The improved dipper tooth is thus adapted for ready and convenient reversal, as the co-operating parts are identical in either position, and when assembled there is afforded a substantially unbroken thickness of metal 60 through the point and base, with a transverse pin securing the parts against endwise displacement. Furthermore, the co-operation of the base and point is through the medium of a relative clamping or sliding co-action, 65 which when at its limit provides opposing

substantially dovetail connections, the effect of which is to eliminate or minimize twisting movement.

Having thus described our invention, we 70 claim:—

1. A reversible point embodying a wedge shape body with full section jaws and a full section vertical web terminating beyond the jaws, said web having an eye near its terminal and having longitudinally extending side 75 bars or panels springing from the crotch of the jaws and stopping short of the eye.

2. A reversible point embodying a wedge shape body with full section jaws and a full section web, the jaws having undercut bevels 80 which are directed laterally.

3. A reversible point embodying a wedge shape body with web connected full section jaws provided with continuous undercut 85 bevels.

4. A reversible point embodying a wedge shape body with full section jaws and a connecting web, the jaws having opposed laterally directed bevels, and the web having side 90 bars or panels in the longitudinal axial plane of the point.

5. A reversible point embodying a wedge shape body with full section jaws and a connecting web, the jaws having continuous laterally directed bevels, and the web terminating 95 beyond the jaws in an arcuate bearing portion.

6. A sectional digging tooth, comprising a base and a point, the base having spaced point receiving arms with point stops perpendicular thereto, the arms having their top and bottom surfaces inclined laterally, and the point having a central web and undercut jaws to frictionally engage the base. 100

7. A base having a divided forwardly inclined point-receiving portion formed with opposed reversely beveled point engaging surfaces, the bevels being directed laterally. 105

8. A base having forwardly inclined arms, the inclination stopping short of the base to 110 provide point stops and flat bearing surfaces to resist twisting movement of the point, said arms having opposed reverse bevels, which are directed laterally.

9. A base having point receiving arms of 115 general trapezoid shape in cross section, their top and bottom surfaces being laterally inclined, said arms having confronting longitudinally extending slots.

10. A sectional digging tooth, comprising 120 a base and a point, the base having point receiving arms, the top and bottom surfaces of which are inclined laterally, said arms being flared in front and having confronting grooves, and a point having a central web 125 with side bars or panels adapted to said grooves, and having undercut jaws which operate to press the arms against the web.

11. A sectional digging tooth, comprising a base and a point, the base having point re- 130

ceiving arms, the top and bottom surfaces of which are inclined laterally, said arms being flared in front and having confronting grooves, and a point having a central web 5 with side bars or panels adapted to said grooves, and having undercut jaws which operate to press the arms against the web, and auxiliary means for locking the point to the base.

10 12. A sectional digging tooth, comprising a base and a point, the base having point receiving arms, the top and bottom surfaces of which are inclined laterally, said arms being flared in front and having confronting 15 grooves, and a point having a central web with side bars or panels adapted to said grooves, and having undercut jaws which operate to press the arms against the web, and a transversely disposed holding pin for securing the point to the base.

13. A sectional digging tooth, comprising a base and a point, the base having spaced point receiving arms of triangular form in side elevation and with substantially flat and 25 parallel surfaces where they join the base, said arms having their point receiving surfaces inclined laterally, the point having a central web which fits the space between the arms and having jaws contoured to frictionally engage the arms and operating to exert 30 side thrust upon the arms sufficient to prevent side motion of the point.

14. A sectional digging tooth, comprising a point and a base, the base having point-receiving arms whereof each is provided with laterally converging point-seating surfaces, and the point having web connected jaws adapted to exert side pressure upon the arms.

40 15. A sectional digging tooth, comprising a base and a detachable and reversible point, the base having reversely beveled point-receiving arms with the bevel directed laterally, and the point having web connected jaws which clamp said arms.

16. A sectional digging tooth, comprising a base and a reversible point, the base having point-receiving arms and point stops, the latter being formed on a curve of which the 50 center is the apex of the point, and the arms having opposing side directed reversely beveled point seating surfaces, the point having web connected full section jaws which straddle the arms with substantial side compression.

55 17. A sectional digging tooth, comprising a base and a point, the base having point-receiving arms the point seating surfaces of which are formed by laterally directed bevels 60 and the point having undercut jaws to rigidly grip the arms.

18. A sectional digging tooth, comprising a base and a point, the base having flaring point-receiving arms with confronting 65 grooves, and the point having undercut jaws

to frictionally grip the arms and having a web, connecting the jaws and provided with tongues adapted to said grooves.

19. A sectional digging tooth, comprising a point and a base, the base having laterally 70 beveled point-receiving arms, and the point having web connected jaws which are beveled to fit the arms.

20. A sectional digging tooth, comprising a point and a base, the base having laterally 75 beveled point-receiving arms, and the point having web connected jaws which are undercut to fit the arms and which exert side pressure on the arms.

21. A sectional digging tooth, comprising 80 a point and a base, the base having a reversely beveled point seating portion, and the point having web connected jaws which are shaped to compressively engage said reversely beveled portion, and positive means 85 for securing the point to the base.

22. A sectional digging tooth, comprising a point and a base, the base having a reversely beveled point seating portion, and the point having web connected jaws with undercut bevels to compressively engage said reversely beveled portion.

23. A sectional digging tooth, comprising a point and a base, the base having a reversely beveled point seating portion, and the point having web connected jaws with continuous undercut bevels to compressively engage said reversely beveled portion.

24. A sectional digging tooth, comprising a point and a base, the base having spaced 100 point receiving arms the top and bottom surfaces of which are reversely beveled, and the point having full section jaws which are correspondingly beveled.

25. A sectional digging tooth, comprising 105 a base and a reversible point, the base having an undercut portion flanked by reversely beveled point receiving arms, the point having full section jaws which compress the arms and having a full section web which 110 takes a bearing in said undercut portion.

26. A sectional digging tooth, comprising a base and a reversible point, the base having an undercut portion flanked by reversely beveled point receiving arms, the point having 115 full section jaws the confronting faces of which are continuously undercut to compressively engage the arms and having a web which fills the space between the arms and takes a bearing in said undercut portion.

27. A sectional digging tooth, comprising a base and a reversible point, the base having reversely beveled point receiving arms, the point having correspondingly beveled jaws and a central web, the web and arms having 125 transversely ranging pin openings.

28. A sectional digging tooth, comprising a base and a reversible point, the base having point receiving arms with reversely formed laterally directed bevels and diagonal tips,

and the point having web connected jaws extending laterally, whereby when the elements are assembled lost motion is eliminated 10 by the compressive action of one element upon the other.

29. A sectional digging tooth of the reversible type, comprising base and point elements whereof one has opposed external reverse bevels and whereof the other has complementary internal bevels, all of said bevels

In testimony whereof we have hereunto signed our names.

LESHER W. VAN BUSKIRK.
PHILIP W. PORTER.
